UNITED STATES PATENT OFFICE.

JAMES F. GORDON, OF ROCHESTER, NEW YORK; MARY A. GORDON EXECUTRIX OF SAID JAMES F. GORDON, DECEASED.

GRAIN HARVESTING AND BINDING MACHINE.

SPECIFICATION forming part of Letters Patent No. 349,842, dated September 28, 1886.

Application filed January 14, 1884. Serial No. 117,461. (No model.)

To all whom it may concern:

Be it known that I, JAMES F. GORDON, of Rochester, in the county of Monroe and State of New York, have invented certain Improvements in Grain Harvesting and Binding Machines, of which the following is a specification.

This invention has reference to those machines in which it is desirable to turn or swing the cut grain horizontally to a binding mechanism at the rear upon the platform or other support, the improvements being designed more particularly for application to low-level or platform binders of the general character represented in my Patent No. 320,348, June 16, 1885, wherein the cut grain, after being delivered at the inner end of the harvester-platform, is turned at right angles, or substantially right angles, so as to lie parallel with the cutter-bar for presentation to the binding mechanism.

The present improvements relate particularly to an improved arrangement of toothed conveyer-chains designed to effect the double purpose of delivering the grain from the harvester-platform and of turning or swinging the same horizontally.

Referring to the accompanying drawings, Figure 1 represents a top plan view of such portions of a harvesting and binding machine as are necessary to an understanding of my invention, the binding devices, the reel, and other parts foreign to the invention being omitted. Fig. 1^a is a vertical section from front to rear on the line *v v* of Fig. 1, showing the abutment against which the grain is carried by the conveying mechanism. Fig. 2 is a longitudinal vertical section on the line *w w* of Fig. 1, showing the mechanism by which motion is imparted to the chains. Figs. 3, 4, and 5 are sectional views on the lines *x x*, *y y*, and *z z*, respectively, showing the folding teeth in different positions. Figs. 6 and 7 are perspective views illustrating the chains and teeth, the latter being shown in their operative and inoperative positions, respectively.

Referring to the accompanying drawings, A represents the main frame, made of an oblong substantially rectangular form, and supported at its inner end by the main driving-wheel B, and at its outer end by the grain or stubble wheel C. The outer end of the frame is pro-

vided at the forward edge with ordinary cutting mechanism, D, and immediately in rear of said mechanism with a horizontal grain-receiving platform, E, commonly known as the "harvester-platform." The cutting mechanism and the harvester-platform are made of the usual length; but, instead of being extended inward to a point near the main wheel, the frame is elongated to admit of the platform and cutters being set outward away from the main wheel in such manner as to leave between the harvester-platform and the wheel a sufficient space to admit of the cut grain being turned horizontally thereon. The space between the harvester-platform proper, which terminates on the line *a*, and the main wheel is occupied by a secondary platform or table, F, forming a continuation of the harvester-platform on a level therewith, and serving to support the grain while being turned and moved to the binder.

The foregoing parts are or may be of essentially the same construction as in my original application above referred to, and the entire binding mechanism proper may also be constructed and arranged in the same manner as in said application.

My improved means for turning and delivering the grain consists in a series of endless toothed chains, H H' H'', &c. These chains, their teeth, and the devices for elevating the teeth are alike in construction. Each chain is arranged to revolve in the same horizontal plane, being carried around the outside of supporting-rollers I, which revolve upon vertical axes. It will be perceived that under this arrangement the chains pass around the supporting-rollers without the rising and falling movement which occurs when they are carried over rollers having their axes arranged horizontally. Each chain is provided at suitable intervals with a series of angular teeth, J, arranged to turn in a vertical plane around a horizontal journal or trunnion, b, formed on the side of the chain-links. Each tooth is made of an L form, with one end, c, pointed, in order that it may readily rise through and act upon the grain, and with the opposite end, d, widened and flattened to form a foot adapted to ride upon the rail, by which the tooth is caused to assume an upright po-

sition. The form of the links, and the manner in which they are connected, is immaterial; but it is preferred to employ links with open centers, having their ends provided with hooks, by which they may be readily connected and disconnected in the same or essentially the same manner as in the various driving-chains now commonly known in the art. It is preferred, as shown in Figs. 6 and 7, to form the journals by which the teeth are carried at the upper edge of the links, the edge being extended upward, as shown, in order that the teeth may be sustained above the body of the link.

15 For the purpose of elevating and sustaining the teeth, stationary tracks or rails K are arranged adjacent to the chains along such portion of their length as it is required to have the teeth act upon the grain. As each tooth 20 is carried forward, its foot encounters the end of the stationary rail, in the manner represented in Fig. 3, whereby the tooth is caused to assume an elevated position and maintained against the resistance of the grain, 25 so as to carry the latter positively forward before it. The movement of the chain causes the tooth in this position to move lengthwise over the rail, as represented in Fig. 2, until the opposite end of the rail is reached, 30 whereupon the tooth escaping therefrom is permitted to turn downward to the position represented in Fig. 4. The chains are arranged to travel below the platform, which is provided with slots L, to admit of the teeth rising 35 through the same to act upon the grain during the required portion of their movement. During the time that the teeth are inoperative—that is to say, during their retrograde movement—they are carried backward beneath the 40 platform, in the manner represented in Figs. 1 and 5, being thus kept out of contact with the grain and protected from the entrance of straw or other obstructions. The pulleys by which the chains are guided may be disposed or arranged in such relations to each other as to cause the chains to move the grain in any desired path. In the present machine it will be perceived that the outer chain, H, extends lengthwise of the harvester-platform near the 45 forward edge to its inner end, thence with two bends or angles backward across the secondary platform to a point near the rear edge, thence along the rear edge of the harvester to the corner at the grain side, and finally forward to the point of commencement. The 50 track and slots are arranged in such manner that the teeth rise to an operative position at the outer or grain end of the platform, and continue to act as they pass inward and backward 55 until the rear corner of the secondary platform is reached. The second chain, H', is arranged in like manner, being encircled by the first and arranged parallel therewith. The third chain, H", which terminates at a point near the inner end of the harvester-platform, passes simply around two pulleys at its extremities in a right line with the inner end of the platform,

and then returns in an inoperative position. The fourth chain, H", is also arranged to travel around two pulleys at its extremities, its teeth 70 operating in a right line. This chain is arranged so that its teeth cease their action upon the grain slightly before those of the chain H". It is to be observed that each of the conveyer-chains is so arranged that its teeth move 75 in an operative position nearer the main wheel than those of the chain next in its rear. In other words, the forward chains act upon the butts of the grain and carry the same farther inward toward the main wheel than the teeth 80 of the rear chains. Owing to this arrangement and to the fact that the forward chains are extended backward across the secondary platform, the grain is moved in a continuing stream first squarely over the harvester-platform to its inner end, and, secondly, backward in a curved path toward the rear edge 85 of the secondary platform, from which it will be introduced to the binder by packing mechanism such as shown at M, or by other suitable appliances. The employment of chains which are continued from the harvester-platform backward beneath the secondary platform is advantageous, first, because of the extreme simplicity and cheapness of the arrangement, and, second, because the grain is but slightly agitated and not subjected to an objectionable thrashing or hulling action. It is also found that in the case of lodged or tangled grain, continuous chains having teeth 90 which engage positively with the grain and which remain in engagement therewith effect the delivery of the grain in a "straighter," 95 more regular, and better condition than is otherwise attainable. 100

In order to assist the chains in delivering the grain in a compact condition, I cover the packing devices by a shield or covering, X, the forward side of which rises somewhat abruptly from the platform, as shown in Fig. 1, 110 so as to form an abutment against which the grain will lodge. The packers serve to lift the accumulated grain at the proper time from the shoulder to the binder-arm in the rear.

Motion may be communicated to the various 115 chains in any suitable manner; but a simple and efficient means for the purpose, and one which is recommended, is that represented in the drawings. One of the pulleys I, carrying each chain, is formed with or secured upon the 120 same shaft with the second wheel, N. A single chain, O, is passed around the series of wheels N, and thence around a wheel, P, applied to the lower end of a vertical shaft, Q. This shaft, mounted in bearings on the main frame, 125 is provided at the upper end with a bevel-pinion, R, driven by a bevel-gear, S. The last-named gear is mounted on a horizontal shaft, T, which is mounted in bearings on the main frame B. Under the above arrangement 130 motion is communicated from the main wheel to the intermediate parts by the chain O, and thence through the pulleys N to the respective carrier-chains. Suitable provision will of

course be made for throwing the driving-chain out of action when it is required to stop the conveyer-chains. If the pulleys N be made of the same size, the several conveyer-chains 5 will be driven at uniform speeds; but if it be desired to drive the conveyer-chains at different speeds the result may be accomplished by making the wheels N of different sizes.

I am aware that it has been proposed to extend a canvas apron lengthwise of a harvester-platform and to carry the same at one end upon a roller arranged in an oblique position. I am also aware that it has been proposed to extend a series of cords lengthwise of a harvester-15 platform, around rollers having horizontal axes, and thence backward at one end of the platform in oblique lines, and to such constructions, neither of which are practically operative, I lay no claim. I believe myself to be the first, however, to employ endless carrier-chains provided with vertically-folding teeth and extended lengthwise of the harvester-platform, and thence in a curved path to effect the turning of the grain in a positive 25 manner after it is delivered from the platform, and present the same to the action of a binding mechanism, as shown in the drawings.

W represents a binder-arm, the needle pivoted to vibrate vertically, in order that it may 30 leave the cord or other binding material around the bundle in a plane at right angles to the length of the cutter-bar, or approximately so.

The packing devices, which constitute part of the binding mechanism, may be omitted, 35 and the binder-arm replaced by any equivalent arm adapted to lay the cord about the gavel in the direction stated.

The binder-arm will be arranged to act with knotting, clamping, and severing devices of 40 any proper character, many devices for the purpose being at present known to every person skilled in the art.

Having thus described my invention, what I claim is—

45 1. In a harvesting-machine, two endless horizontally-traveling conveyer-chains provided with vertically-movable teeth, one chain

arranged to encircle the other, substantially as described.

2. In combination with the series of endless 50 chains, the horizontally-revolving wheels to sustain the same, the driving-wheels N, and the driving-chain O common to the series of wheels, as described.

3. The combination, in a harvester, of the 55 main or ground wheel, the wheel P, geared thereto and driven therefrom, a series of conveyer-chains, driving-wheels for the respective chains, and a single driving-chain, O, communicating motion from the wheel P to the 60 several wheels N, as described and shown.

4. In a harvester, one or more horizontal revolving toothed conveyer-chains extending lengthwise of the harvester-platform, in rear of the cutters, and thence in a curved or oblique path in the supplementary platform, in combination with one or more toothed conveyer-chains extending horizontally in a straight line within the harvester-platform only, substantially as and for the purpose set forth. 70

5. In combination with a series of conveyer-chains, whereby the grain-stalks are carried first in a straight line in rear of the cutters, and thence in a curved or oblique path in the auxiliary platform, a vibratory binder-arm, 75 and a revolving toothed packer located between the delivery end of the conveyers and the binder-arm.

6. In combination with a series of endless toothed conveyer-chains, substantially as herein described, whereby the grain-stalks as they are cut are carried continuously across the platform in rear of the cutters, and thence in a curved or oblique path toward the binder, a shoulder or abutment rising above the platform, and secondary conveying or packing mechanism acting between the delivery end of the conveyers and the binding mechanism to deliver the grain over the abutment, substantially as described. 85

JAMES F. GORDON.
